CLAIM

The ornamental design for a portable non-destructive test instrument, as shown and described.

DESCRIPTION

FIG. 1 is a first isometric view of a portable non-destructive test instrument, showing a side door in a closed position. FIG. 2 is the first isometric view of the portable non-destructive test instrument, showing the side door in an open position.

FIG. 3 is a second isometric view of the portable non-destructive test instrument, showing the side door in the closed position.

FIG. 4 is the second isometric view of the portable non-destructive test instrument, showing the side door in the open position.

FIG. 5 is a front view of the portable non-destructive test instrument, showing the side door in the open position.

FIG. 6 is a back view of the portable non-destructive test instrument, showing the side door in the open position.

FIG. 7 is a right side view of the portable non-destructive test instrument, showing the side door in the open position.

FIG. 8 is a left side view of the portable non-destructive test instrument, showing the side door in the open position.

FIG. 9 is the left side view of the portable non-destructive test instrument, showing the side door in the closed position.

FIG. 10 is a top view of the portable non-destructive test instrument, showing the side door in the open position; and, FIG. 11 is a bottom view of the portable non-destructive test instrument, showing the side door in the open position.
